UNITED STATES PATENT OFFICE.

NELS P. SJOBRING, OF CHICAGO, ILLINOIS.

METAL-ROLLING MACHINE.

1,155,522.

Specification of Letters Patent.

Patented Oct. 5, 1915.

Application filed July 28, 1913. Serial No. 781,608.

To all whom it may concern:

Be it known that I, NELS P. SJOBRING, a citizen of the United States of America, and a resident of Chicago, county of Cook, and 5 State of Illinois, have invented certain new and useful Improvements in Metal-Rolling Machines, of which the following is a specification.

The main objects of this invention are to 10 provide a metal rolling machine adapted to form metal strips into suitable shapes for many uses, such as in structures requiring formed metal strips, for example, moldings; to provide in such machine means for driving 15 a plurality of pairs of dies, said dies being adapted to form and feed the metal through the machine, and the said means being arranged to permit different dies to rotate at like peripheral speeds regardless of variations 20 in their respective diameters; to provide a metal forming machine in which a plurality of sets of graduated dies are employed, adapted for operating dies of a great variety of sizes and handling stock of 25 different widths; to provide a machine of this class which does not require individual adjustment of each pair of dies each time a new strip of stock is started through the machine.

30 Figure 1 is a plan view of a metal forming machine constructed according to this invention. Fig. 2 represents a side elevation of the machine. Fig. 3 represents an end elevation. Fig. 4 shows a sectional 35 tail of gearing employed in the machine.

In metal rolling machines of this general type it is customary to draw the stock between pairs of roller dies which are free to rotate according to the speed of the metal 40 operated upon, or the stock is fed by positively driven dies. The former case necessitates an adjustment of the dies each time a new piece of stock is fed into the machine, as it is necessary to first separate the 45 operating dies and then to successively adjust toward each other each pair of dies as one end of the stock is drawn through the machine and gradually brought to the desired shape. In the latter case the dies must 50 be of exactly the correct proportions or driven at such speeds that the metal will not become distorted while being operated upon.

The present invention provides a machine 55 of this class wherein the relative speed between a plurality of sets of dies is auto-

matically controlled as required by the work performed. It is also possible with the present invention to employ in a single machine driven dies of many different sizes so 60 as to shape either narrow or wide strips of metal.

Referring to the drawings, the side frames of the machine are designated by the numerals 1 and 2. These frames are connected together by tie bars 3 and slidably mounted on the tie bars is an adjustable guide frame 4. The frame 4 is adjustable for the purpose of accommodating any desired sizes of dies and width of metal stock. 70 The dies indicated by the numeral 5 in Figs. 1 and 3 are arranged in coöperating pairs, and it may be seen from Fig. 1 that the pair of dies at the right of the machine, at which side the stock to be operated upon enters 75 the machine, are more nearly cylindrical than the dies at the left of the machine. The intermediate pairs of dies are graduated so that after the metal leaves the first set of dies it will be successively operated 80 upon by the different sets of dies and gradually brought to the desired shape by the pair of dies at the left (Fig. 1).

Power is applied to the machine through a pulley 6 fast to a drive shaft 7 journaled 85 in frames 1 and 2. Shaft 7 carries fast a pinion 8 meshing with gears 9 and 10 fast to shafts 11 and 12 journaled in bearings 13. Pinions 14 on shafts 11 and 12 mesh with gears 16 which are mounted on die supporting 90 shafts 17. The gears 16 through intermediate pinions 18 serve to communicate movement to gears 19 and 19.1 also mounted on die supporting shafts 17. Located above each die supporting shaft are companion die 95 supporting shafts 20. The shafts 17 and 20 are adjustable toward and away from each other to accommodate dies of different diameters, the means for adjusting the shafts being screws 21 passing through the frame 100 2 and adjustable frame 4 and engaging blocks 22 slidably mounted in uprights 24. The intermediate gears 18 are carried by shafts 25 journaled in blocks 26, also slid- 105 able in the uprights 24 secured to frame 2. Blocks 26 are adjustable by means of screws 27 and 28. Screws 27 are threaded through flange 29 of frame 2, while the screws 28 are threaded through the heads of bolts 30 secured to uprights 24 as shown in Fig. 2. 110 Shafts 11 and 12 are also adjustable in their supports on frames 1 and 2, in order that

pinions 14 may be properly meshed with gears 16 when the dies are moved toward or away from each other, in the same manner and for the same purpose that pinions 18 5 and their supporting shafts are adjustable.

To secure frame 4 at any desired point along tie bars 3 it is provided with a separate clamping member 31 (Fig. 3) passing below tie bars 3 and adjustably secured to 10 the frame 4 by bolts 32. Thus by means of these bolts the member 31 may be caused to tightly grip the tie bars 3.

A clutch 33 is provided, operating by a treadle 34 (Fig. 3) for the purpose of connecting and disconnecting pulley 6 from 15 drive shaft 7 as required for starting and stopping the machine.

The gears 16 and 19 are driven by frictional engagement with their respective 20 shafts 17, the specific construction employed for this end being shown in Fig. 4. Each gear 16 has a pair of cone surfaces 35 and 36 for engagement with exterior conical surfaces 37 and 38 on a sleeve 39, splined to a 25 shaft 17, and a collar 40 surrounding the reduced portion 41 of sleeve 39 and splined to said sleeve. The reduced part 41 of sleeve 39 is threaded at its outer end for the reception of a nut 42. By means of this nut the 30 conical surfaces 37 and 38 respectively of sleeve 39 and collar 40 may be engaged with any degree of frictional contact with the conical surfaces 35 and 36 of gear 16. It may be seen from this construction that it 35 is possible for gears 16 to rotate at a different rate than their supporting shafts 17, but that such relative rotation cannot result in turning nuts 42 as the latter are not in contact with gears 16 but are spaced therefrom 40 by collars 40 which rotate with shafts 17 and sleeves 39. The gear 19.1 at the left-hand end of the machine is preferably secured to its supporting shaft 17 and therefore controls the rate of speed through the 45 machine of the material acted upon.

In operating the device the metal stock to be operated upon is caused to enter the machine between the frames 2 and 4 at the right side of Fig. 1. As it passes between 50 the first set of dies it is but slightly bent, but is successively acted upon by the succeeding sets of dies until emerging from the lefthand end of the machine in the desired form.

55 The lower dies being driven through frictional engagement with their respective supporting shafts, the rate of speed of stock passing through the machine will be uniformly maintained, due to the fact that the 60 rotation of the respective dies is frictionally regulated to accommodate the movement of the stock regardless of differences in the diameters of the respective pairs of dies. If it is desired to change the dies for operating 65 upon a different size of stock this may be

done by properly adjusting shafts 17 and 20 toward or away from each other, and also adjusting the frame 4 along the tie bars 3 so that it may, with frame 2, act as a guide suitable for the particular width of the material operated upon. 70

Although but one specific embodiment of this invention has been herein shown and described, it will be understood that numerous details of the construction shown may 75 be altered or omitted without departing from the spirit of this invention as defined by the following claims.

I claim:

1. In a machine of the class described the 80 combination of a continuous positive gear train, a series of rolls each frictionally driven connected therewith, and a series of idler rolls to coact with said frictionally driven rolls to reform metal strips passed 85 therebetween.

2. In a machine of the class described the combination of a continuous positive gear train, a series of frictionally driven rolls any one of which is capable of differential 90 movement with respect to the others without interfering with the drive of the others, and a series of idler rolls adapted to coact with said frictionally driven rolls to reform metal passed 95 therebetween.

3. In a machine of the class described the combination of a plurality of pairs of roller dies, means for frictionally driving one of each pair of said dies, the remaining die of each pair of dies adapted to be driven by the 100 material operated upon, and adjustable means above and below said pairs of roller dies for adjusting the same.

4. In a device of the class described the combination of a supporting frame, an adjustable sliding frame thereon, uprights in said frames, a plurality of movable members in each of said uprights adapted to be vertically adjusted so as to independently move toward or away from each other, a plurality of pairs of upper and lower roller dies journaled in said members, and frictional means for independently driving each of said lowermost dies. 105

5. The combination of a main frame, a 110 slideable auxiliary frame mounted thereon, a series of graduated pairs of roller dies adjustably supported between said frames, a plurality of gears frictionally connected to, and adjustable with certain of said roller dies, and a plurality of adjustable pinions meshing with said gears to form a continuous gear train. 115

6. In a metal rolling machine of the class described a main frame, a movable frame mounted thereon, shafts mounted on said frames, a plurality of dies mounted on said shafts between said frames, and frictional driving means splined on one end of each 120 of said shafts comprising a sleeve, a gear 125

ring frictionally engaging said sleeve, a friction collar splined on said sleeve between said sleeve and ring, and adjustable means on the end of said sleeve for retaining said 5 collar in frictional contact with said ring.

7. In a machine of the class described a main frame, main driving gears, a plurality of pairs of upper and lower roller dies, said main gears and dies mounted between the 10 side walls of said main frame, a slidably adjustable auxiliary frame mounted on said

main frame between said gears and dies, a gear train driven by said gears disposed on the outside of said main frame, and frictional driving connections between each of 15 said lower dies and said gear train.

Signed at Chicago this 23d day of July, 1913.

NELS P. SJOBRING.
